UNITED STATES PATENT OFFICE.

CLAYTON E. FREDERICKSON, OF SAN FRANCISCO, CALIFORNIA, ASSIGNOR OF ONE-HALF TO GRACE C. STENGER, OF BERKELEY, CALIFORNIA.

ROTARY-CYLINDER ENGINE.

1,088,017.

Specification of Letters Patent. Patented Feb. 24, 1914.

Application filed January 31, 1913. Serial No. 745,430.

To all whom it may concern:

Be it known that I, CLAYTON E. FREDERICKSON, residing at San Francisco, in the county of San Francisco and State of California, have invented certain new and useful Improvements in Rotary-Cylinder Engines, of which the following is a specification.

My invention is an improved two-cycle combustion engine of the rotary cylinder type in which the crank shaft remains stationary while the cylinders revolve around the same.

Generically the invention provides a motor of the type stated in which the crank case forms the fuel supply reservoir from the carburetor and from which reservoir the fuel is passed into the compression space of the cylinder or cylinders, through the invention of a controlling valve of special design, that forms an oscillatable dam or shut-off between the lower end of the respective cylinder and the crank case. It is in this feature of the apparatus that one of the essentials of my present invention resides.

Another important feature of my invention lies in the provision of an especially constructed muffler so designed with relation to the engine proper as to have its weight balanced and so attached to the cylinders as to rotate with the same.

Again the invention has for its object to simplify the arrangement of parts, reduce the cost of construction, and increase the efficiency of operation of the engine, and to provide an engine that is especially adapted for use in aerial work.

In its more detail nature, the invention also resides in those novel details of construction, combination and arrangement of parts, all of which will be first fully described and then be specifically pointed out in the appended claims, reference being had to the accompanying drawings, in which:—

Figure 1 is a central vertical longitudinal section taken on the line 1—1 of Fig. 2. Fig. 2 is a vertical cross section taken on the line 2—2 of Fig. 1. Fig. 3 is a horizontal section on the line 3—3 of Fig. 1. Fig. 4 is a vertical cross section on the line 4—4 of Fig. 1. Fig. 5 is an enlarged detail perspective view of one of the valve guides for the oscillating valve or cutoff, partly in section. Fig. 6 is an enlarged detail perspective view of one of the oscillating valves.

Fig. 7 is a detail perspective view of the removable guide segment. Fig. 8 is a diagrammatic view of the ignition circuits. Figs. 9 to 12 inclusive are diagrammatic views of one cylinder showing the relative motion between the cylinders and crank shaft and illustrating the cycle of operation of the engine.

Referring now to the accompanying drawings in which like numerals of reference designate like parts in all the figures, 1 and 2 are the stationary frame supports, the support 1 having a collar 3 that is keyed or otherwise secured to the hollow crank shaft 4 so as to hold the same stationary.

5 designates the crank pin to which the connecting rods 53 are connected.

The crank shaft 4 is shouldered at 6 to receive one element 7 of a ball bearing, the other element 8 of which is set into a recess or socket in one of the side or cap plates 9 of the crank case 11. The bearing elements 7 and 8 have ball races to receive the anti-friction balls 10. The crank pin 5 has a reduced threaded end 12 to which the crank member 13 is secured by the jam nut 14, or otherwise, and the crank member 13 has a projection 15 shouldered to receive one element 16 of a bearing member whose other element 18 is fitted into a recess 19, of the crank case cap plate 20, the bearing elements 16 and 18 having the anti-friction balls 17 located between them.

The cap plate 20 has a central enlargement that is bored at 21 to receive the projecting end of the crank member 15 and also to receive the lug 22 that is carried by the flange 23 of the short stub shaft 25 that carries the propeller. The flange 23 is bolted at 24 to the cover 20, and the shaft 25 is threaded to receive the propeller hub 26 which is secured in place by jam nuts 27 and 28, and which carries the propeller blades 29, the blades being secured to a flange of the hub 26 by bolts 30, or otherwise, as may be desired.

One element 31 of an anti-friction bearing is carried on the shaft 25, while the other element 33 is mounted in a socket portion 34 of the frame 2, the balls 32 being located between the members 31 and 33.

The crank case 11 is provided with bored projections 35 to receive the cylinders 57 and they are also counter-bored at 36 to receive the oscillating valve guides 37, the lat-

ter being securely bolted in place as best indicated in Fig. 1 of the drawings. The guides 37 have segmental arc portions 39 separated by a passage 38 through which 5 the body of the valve 42 projects, and the guides 39 coöperate with guides 40 that are secured by bolts 41 to form a guideway for the segmental arc flanges 43 of the valve 42. The valve 42 is of the peaked type and has 10 a portion 44 cut away or otherwise formed to act as the valve proper to open and close communication between the interior of the crank case 11 and the interior of the compression space of the cylinders 57. The 15 valve 42 is bored at 45 and opened at 46 to receive the roller bearing member 47 through which, and through the opening 46, the piston connecting rod 53 passes. The roller 47 floats in the bore 45 to have a slight 20 amount of lateral play, and it has spindles 48 on which caps 52, are mounted, and held in tight frictional contact with the sides of the valve 42 by springs 49 on the spindles 48. The springs 49 are held in place by 25 washers 50 and pins 51, and also serve to keep the roller 47 centered in the bore 45.

The connecting rods 53 are secured to the crank bearings 55 by threading the same into the bearings as at 56 and providing jam 30 nuts 54 to retain the connection.

Each cylinder 57 is divided into a working chamber and a compression space, by the respective piston 58. The connecting rod 53 is connected to the piston 58 by the usual 35 pin connection 59, and the cylinder 57 is provided with ports 60—61 that are controlled by the piston 58 and are connected by by-passes 62 to convey the compressed new charge from the compression space in 40 back of the piston into the working chamber when the piston ports 63 register with the port 60, and when the port 61 is uncovered by the piston 58, the piston head is provided with the usual baffles 64 to shoot the 45 new charge toward the cylinder head 67 and blow out the old charge through the exhaust ports 59 when they are uncovered by the piston.

66 designates the cooling device for the 50 usual purpose, and 68 designates the spark plug of the ignition system.

The exhaust ports 69 communicate through a connecting casting 70 having ducts 71 with the muffler 72 which is, as before stated, of a special construction adapted particularly for use in connection with this engine. The muffler 72 is constructed of a ring-like hollow sheet metal body separated into a series of sections, depending 55 upon the number of cylinders, by partitions 73 adjacent to the exhaust ports 69 of the engine, and the muffler is provided with a corresponding set of discharge openings 75, the space traversed by the gases from the 60 partition 73 to the outlet 75 being formed

into a zigzag passage by projecting partial partitions 74 arranged in zigzag form as best indicated in Fig. 4 of the drawings.

76 designates the magneto which may be mounted on the frame 1 and driven from 70 the rotating crank case 11 through the medium of gear connections, one form of which is best illustrated in Fig. 1 of the drawings, by reference to which it will be observed that the shaft 77 of the magneto carries a 75 gear 78 which meshes with a gear 79, secured at 80 to the cap plate 9, to turn with it.

81 is the commutator insulation which is mounted on the cap plate 9 to turn with it and has the desired number of contacts 82 80 to be engaged by the contact 83 that is connected through a wire 85 with the magneto. The contacts 82 are connected with the respective spark plugs 68 by wires 84.

86 is the carbureter which may be of any 85 desired construction and connected in any suitable way, as for example at 87 to the hollow shaft 4, so that the mixture from the carbureter may pass into the crank case 11.

The operation of the invention will be 90 clear by following the same in connection with one cylinder, since the operation in all cylinders is identical, differing only in the relative time of the commencement of the cycle of operation.

In Figs. 9 to 12 inclusive, I have indicated one cycle of operation. If the parts are positioned as indicated in Fig. 9 and assuming that the case 11 is filled with working agent under atmospheric pressure, and the compression space of the cylinder 57 having been filled with a compressed new charge, such charge will be seen to be passing into the working chamber of the cylinder through the ports 63—60, by-pass 62 and ports 61. 100 At the same time the old charge will be passing out through the exhaust ports 69. Communication between the carbureter of the crank case 11 and the compression space of the cylinder 57 will be cut off by the oscillating 105 valve 42 since the valve 44 will not be open. Now as the cylinder turns with relation to the crank in the direction of the arrow, to move toward the position shown in Fig. 10, the valve 42 will be rocked to open the 110 port 44 and permit a charge to be drawn into the compression space of the cylinder 57 during the suction stroke of the piston 58, the passage of the charge into the cylinder being assisted by the centrifugal force due 115 to the rotation of the crank case and cylinders. As the piston 58 reaches the limit of its compression stroke, it moves through the position shown in Figs. 11 and 12, to a position such as illustrated in the upper 120 cylinder of Fig. 2, with the valve 42 in alignment with the longitudinal axis of the cylinder. From this time until the piston again reaches the position shown in Fig. 9, communication between the crank case 11 and 125

the compression space of the cylinder will remain cut off, this being during the working stroke of the piston 58.

It will be noted that the valve 42 is not what is known in mechanics as a slide valve, that is, one which reciprocates in a rectilinear direction, but is an oscillating valve, *i. e.* one that oscillates in a circular arc path about a given center. It will be observed that the center of motion of the valve 42 is preferably located and approximately on the circle of rotation of the crank pin 5, as will be most apparent by an inspection of Figs. 1 and 9. This gives a quick short action to the valve so as to enable it to operate with the greatest efficiency and minimum wear.

By virtue of the fact that the cylinders rotate, the contact between the under surfaces of the guides 39 and the upper surfaces of the flanges 43 of the valves 42 will be increased as the speed of the engine rises due to the action of centrifugal force which continuously tends to hold the flanges 43 in tight contact with the guides 39 thereby reducing the liability of leakage between the compression space of the cylinder and the interior of the crank case 11.

Any suitable ignition system may be employed in connection with the engine, and any suitable lubricating system, as in this application I make no claim, *per se*, to any special type of ignition system or lubricating system.

From the foregoing description taken in connection with the accompanying drawings, it is thought the complete construction, operation, and advantages of the invention will be apparent to those skilled in the art to which it relates.

It might be mentioned in conclusion that when the lubricant is introduced via the crank case, in order to prevent accumulation of the lubricant it may be injected into the working chamber by means of a pipe connection 88 and back check valve 89.

What I claim is:—

1. In an engine of the type stated, a crank case, a cylinder mounted thereon to communicate with the interior of the crank case, said cylinder having a piston controlled exhaust port, a piston operating in the cylinder to divide the same into a working chamber and a compression space, a crank shaft, a connecting rod between the crank shaft and the piston, means for admitting working agent into the crank case, and means for passing the charge from the compression space into the working chamber of the cylinder; and an oscillatable cut-off and valve member co-operative with the connecting rod to close off communication between the compression space and the interior of the crank case during the working stroke of the piston said cut off and valve member

comprising a peaked body having a segmental arc flange provided with a port and a valve seat member against which said flange bears, said valve seat member being located between the flange and the working cylinder, and the peak of said peaked member extending inwardly from the crank case toward the head of the cylinder whereby, when said crank case and cylinder are rotated, the centrifugal force will hold said oscillatable cut off and valve member seated to prevent leakage between the crank case and the compression space of the cylinder.

2. In an engine of the type stated, a crank case, a cylinder mounted thereon to communicate with the interior of the crank case, said cylinder having a piston controlled exhaust port, a piston operating in the cylinder to divide the same into a working chamber and a compression space, a crank shaft, a connecting rod between the crank shaft and the piston, means for admitting working agent into the crank case, and means for passing the charge from the compression space into the working chamber of the cylinder; and an oscillatable cut-off and valve member co-operative with the connecting rod to close off communication between the compression space and the interior of the crank case during the working stroke of the piston, said cut-off and valve device comprising a peak-like body having segmental arc flanges, a guide member for receiving said flanges, means securing said guide member in place, said peak-like body having an open head portion, a cylindrical body held in said head portion, said body having a bore for the connecting rod to pass through said peak-like body being located with its head portion projected into said cylinder, and said guide member being located in a position between said segmental arc flanges and the cylinder whereby centrifugal force will act to hold said flanges in contact with said guide member against the pressure in the compression space of the cylinder during rotation of the crank case and cylinder around the crank shaft.

3. In an engine of the type stated, a crank case, a cylinder mounted thereon to communicate with the interior of the crank case, said cylinder having a piston controlled exhaust port, a piston operating in the cylinder to divide the same into a working chamber and a compression space, a crank shaft, a connecting rod between the crank shaft and the piston, means for admitting working agent into the crank case, and means for passing the charge from the compression space into the working chamber of the cylinder; and an oscillatable cut-off and valve member co-operative with the connecting rod to close off communication between the compression space and the interior of the crank case during the working stroke

115

of the piston, said cut-off and valve device comprising a peak-like body having segmental arc flanges, a guide member for receiving said flanges, means securing said 5 guide member in place, said peak-like body having an open head portion, a cylindrical body held in said head portion, said body having a bore for the connecting rod to pass through, and means for applying balanced 10 pressures to the ends of said cylindrical body to tend to keep it centered in the head said peak-like body projecting with its head into said cylinder, all being arranged whereby the action of centrifugal 15 force will hold said segmental arc flanges in contact with said guide member against the pressure in the compression space of the cylinder during operation of the engine.

4. In an engine of the type stated, a crank 20 case, a cylinder mounted thereon to communicate with the interior of the crank case, said cylinder having a piston controlled exhaust port, a piston operating in the cylinder to divide the same into a working chamber, 25 and a compression space, a crank shaft, a connecting rod between the crank shaft and the piston, means for admitting working agent into the crank case, and means for passing the charge from the compression 30 space into the working chamber of the cylinder; and an oscillatable cut-off and valve member coöperative with the connecting rod to close off communication between the compression space and the interior of 35 the crank case during the working stroke of the piston, said cut-off and valve device comprising a peak-like body having segmental arc flanges, a guide member for receiving said flanges, means securing said 40 guide member in place, said peak-like body having an open head portion, a cylindrical body held in said head portion, said body having a bore for the connecting rod to pass through, and means for applying balanced 45 pressures to the ends of said cylindrical body to tend to keep it centered in the head, and means forming a coöperative part of said last named means for preventing leakage of fuel through said head portion openings.

5. In an engine of the type stated, a crank 50 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and 55 means for passing the charges from the compression spaces into the working chambers of the cylinders; an oscillatable cut-off and valve device mounted at the places of connection between each of the respective cylinders and the crank case and coöperative with the respective connecting rods to close off communication between the compression space of the respective cylinder and the crank case during the working strokes of the pistons, means for holding the crank shaft stationary to permit rotation of the crank case and cylinders around the 60 shaft, and means for admitting working agent into the crank case, together with a muffler mounted on and rotatable with the cylinders, said muffler having communication with the exhaust ports of the cylinders.

6. In an engine of the class described, a

the respective connecting rods to close off communication between the compression space of the respective cylinder and the crank case during the working strokes of the pistons, means for holding the crank shaft stationary to permit rotation of the crank case and cylinders around the shaft, and means for admitting working agent into the crank case each of said oscillatable cut-off and valve devices including a peaked member projected into the respective working cylinder, a member carried by said peaked member through which the respective connecting rod passes, said peak-like body including segmental arc flanges, and a guide and seat member against which said flanges bear, all being arranged whereby when the engine is in operation centrifugal force will act on said peaked members to hold their flanges in contact with their respective guide and seat members against the pressures in the compression spaces of the cylinders.

6. In an engine of the type stated, a crank 70 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 75 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

7. In an engine of the class described, a 80

8. In an engine of the type stated, a crank 85 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 90 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

9. In an engine of the type stated, a crank 95 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 100 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

10. In an engine of the type stated, a crank 105 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 110 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

11. In an engine of the type stated, a crank 115 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 120 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

12. In an engine of the type stated, a crank 125 case, a set of cylinders mounted on and in communication with the crank case, a piston operating in each cylinder to divide the respective cylinder into a working chamber and into a compression space, a single crank shaft, a connecting rod between the crank shaft and each piston, each of said cylinders having piston controlled exhaust ports, and means for passing the charges from the compression spaces into the working chambers of the cylinders; an oscillatable cut-off and valve device mounted at the places of connection between each of the respective cylinders and the crank case and coöperative with the respective connecting rods to close off communication between the 130 compression space of the respective cylinder and the crank case during the working strokes of the pistons, means for holding the crank shaft stationary to permit rotation of the crank case and cylinders around the shaft, and means for admitting working agent into the crank case, together with a muffler mounted on and rotatable with the cylinders, said muffler having communication with the exhaust ports of the cylinders.

7. In an engine of the class described, a

- crank case comprising an annular body and cap plates fitted thereto, a stationarily held crank shaft, anti-friction bearings between said crank shaft and said cap plates on which said crank case is adapted to turn, a set of cylinders mounted on said crank case and radiating from the axial line of said crank shaft, each of said cylinders having a compression space adapted to communicate with the crank case, a piston operating in each cylinder, a connecting rod for each piston to connect it with the crank shaft, an oscillatable cut-off and valve device for each cylinder for controlling the communication between the compression space of the respective cylinder and the crank case, and co-operative connections between the respective cut-off and valve device and its connecting rod, said cylinders having piston controlled exhaust ports and piston controlled by-passes between the respective compression space and working chamber of the cylinders, a stationary supporting frame in which said crank shaft is mounted, a stub shaft connected with said crank case to aline with the axis of the crank shaft, a stationary frame in which said stub shaft is rotatably mounted, said stub shaft adapted to transmit the power of the engine said oscillatable cut off and valve device including segmental arc flanges, and a guide and seat member for the respective valve device coöperating with said flanges whereby the action of centrifugal force when the engine is in operation will seat said flanges in contact with said guide against the pressure in the compression spaces of the cylinders.
8. In an engine of the class described, a crank case, comprising an annular body and cap plates fitted thereto, a stationarily held crank shaft, anti-friction bearings between said crank shaft and said cap plates on which said crank case is adapted to turn, a set of cylinders mounted on said crank case and radiating from the axial line of said crank shaft, each of said cylinders having a compression space adapted to communicate with the crank case, a piston operating in each cylinder, a connecting rod for each piston to connect it with the crank shaft, an oscillatable cut-off and valve device for each cylinder for controlling the communication between the compression space of the respective cylinder and the crank case, and co-operative connections between the respective cut-off and valve device and its connecting rod, said cylinders having piston controlled exhaust ports and piston controlled by-passes between the respective compression space and working chamber of the cylinders, a stationary supporting frame in which said crank shaft is mounted, a stub shaft connected with said crank case to aline with the axis of the crank shaft, a stationary frame in which said stub shaft is rotatably mounted, said stub shaft adapted to transmit the power of the engine, a hollow-ring like muffler mounted on said cylinders to turn with the same, each of said cut-off and valve devices including a portion projecting into the respective cylinder, a cylindrical bearing member mounted in said projecting portion and bore to permit passage of the connecting rod, and means for applying a balanced force to each end of said cylindrical member to tend to maintain it centralized said oscillatable cut off and valve device including segmental arc flanges, and a guide and seat member for the respective valve device coöperating with said flanges whereby the action of centrifugal force when the engine is in operation will seat said flanges in contact with said guide against the pressure in the compression spaces of the cylinders.
10. In a rotary cylinder internal combustion engine of the two cycle type, a rotatable crank case, a cylinder mounted on the crank case and in communication therewith at one end, a valve seat member mounted in said
